A. J. GIBBONS

ELECTRIC WATER HEATER

Filed June 5, 1926

UNITED STATES PATENT OFFICE.

ARTHUR J. GIBBONS, OF INDIANAPOLIS, INDIANA.

ELECTRIC WATER HEATER.

Application filed June 5, 1926. Serial No. 113,999.

My invention consists in certain improvements in the construction and arrangement of parts of electric water heaters, whereby a heater of such character is provided which not only is comparatively inexpensive and simple in structure, but which is proof against water leakage in operation and thus proof against any short-circuiting of the heating current caused by such leakage all as 10 will hereinafter be more fully described and claimed.

Referring to the accompanying drawings which are made a part hereof and on which similar reference characters indicate similar 15 parts,

Figure 1 is a vertical section through a water heating unit on the dotted line 1—1 in Figure 2,

Figure 2, a similar section on the dotted 20 line 2—2 in Figure 1, and

Figure 3, a diagrammatic view showing the arrangement of the water circulating coils more clearly.

In said drawings the portion marked 10 25 indicates the base, 11 heating units and 12 the water supply pipe.

The base 10 is a suitable casting or stamping adapted to support and carry the parts. The heating units 11 are supported from a 30 cap 20 of insulating material in the top of casing 35 and each consists of a nonfusible core surrounded by heating generating electric wires of any appropriate character such as, for example, chromium nickel, which has 35 been found desirable for the purpose. There

are preferably two of such heating units (but any desired number may be employed) mounted side by side a short distance apart and connected at their top to said cap 20.

40 The electrical winding 21 passes from one core to the other through a slot 22 in said cap. Electric current conducting wires 14 and 15 connect with binding posts 16 and 17, which in the accompanying drawing are

45 shown on top of said cap 20, but which may be located at any convenient point but preferably at some point on the side or bottom where the binding posts 16 and 17 and terminals of winding 21 will be subjected to the

50 least heat and to which the terminals of the windings 21 are respectively connected as shown. A cover 18 is secured by a screw 19 over an opening in the base 10 provided for access to the interior, for any requirement, 55 as will be readily understood.

The water supply pipe 12 leads from any

source of supply, being preferably provided with a cup shaped socket 25 of well known construction adapted to be slipped over the end of any household water spigot. The device is supported on a bracket 26 preferably attached to the water spigot or some other convenient place adjacent to where the hot water will be needed for use. This arrangement of bracket 26 may serve a double purpose of support for the water heater and ground connection for the electric current. The fluid conducting coils are constructed approximately as follows: the discharge spout 30 is suitably connected to the discharge end of the inner coils tube 29 near either the top or bottom, depending upon the direction of winding, said tube is then coiled around one of the heating units, crosses over and is coiled around the next heating unit 60 65 and so on through the series. The inner surface of each coil being electrically insulated, by distance or otherwise, from the said heating units. After completing the windings of the inner coils the tube is carried out and a larger outer or preheating coil 27 is wound over and to enclose all the inner coils and 70 75 heating units said preheating coil being insulated from the outer case by a layer of asbestos or other suitable insulating material 80 85 28. The said preheating coil preferably terminating with a coil of tube on top of and covering the top of all the inner coils and heating units, the end of said tube extending through the outer shell to connect with tube 90 95 12, the source of water supply.

This water coil, therefore, comprises three or more coils, one surrounding each of the heating units, in close relation thereto, and an outside coil surrounding all of said heating units and inner coils, the outside coil serving as a pre-heater for the water before it enters the inner coils and as an insulation between said inner coils and the casing of the device.

100 As will be noticed by an inspection, the discharge spout 30 has a restricted outlet which is for the purpose of retaining a portion of the volume of fluid in the coils at all times.

105 In operation, the current being turned on and supplied through the wires 14 and 15 it will generate heat in the heating units and the water being turned on and passing through the coils will first be heated to a 110 moderate degree in the outside coil and then will pass through the coil surrounding one

of the heating units and from that to the other coils surrounding the other heating units so that by the time it reaches the discharge spout 30 it has been heated to a temperature that may be substantially predetermined by the current supplied to the heating units and the volume of water flowing through the coils around said heating units. By this means a very ready and convenient water heater is provided and one adapted for use without any extensive fittings and one that may conveniently be applied wherever needed without material expense, and one in which the leakage of water 15 within the device is effectively prevented.

Interposed in wire 14 and binding post 16 is a thermal fuse 33 provided to break the electric circuit at a predetermined temperature as when the current is inadvertently 20 left on after the water is turned off, thus guarding against accidental injury to the device.

It will be obvious to those skilled in the art that various changes may be made in my 25 device without departing from the spirit of my invention, and I, therefore, do not limit myself to what is shown in the drawings and described in the specification, but only as indicated in the appended claims.

Having thus fully described my said invention, what I claim as new and desire to secure by Letters Patent, is:

1. A water heater comprising a plurality of heating units, a pipe wound individually 35 about each of the heating units in succession and then about all of the heating units, and

a casing enclosing said coils, substantially as set forth.

2. A portable water heater comprising a plurality of heating units, a heating coil 40 snugly surrounding each of said heating units, another heating coil snugly surrounding all of said heating coils, a casing enclosing said coils, said coils being integrally connected and having one end forming an 45 entrance and the other end an outlet for fluid to be heated, the outlet end being constricted for retaining a portion of the volume of the coils within the same at all times, substantially as set forth. 50

3. A water heater comprising a pair of electric heating units, tubing coiled in one direction snugly around one heating unit and in the opposite direction around the other heating unit and also being coiled 55 around both of said heating units and said coils, substantially as set forth.

4. An electric water heater comprising a casing, a plurality of heating elements within said casing, a water circulating coil fitting snugly about each of said heating elements, a larger circulating coil fitting snugly about the first-mentioned coils, said coils being formed of a continuous section of pipe having one end forming an inlet and the 65 opposite end forming an outlet from the heater, substantially as set forth.

In witness whereof, I have hereunto set my hand at Indianapolis, Indiana this 11th day of May, A. D. nineteen hundred and 70 twenty-six.

ARTHUR J. GIBBONS.
